DESIGN.

W. M. IRKPATRICK.

MODEL OF A PIONEER FARM.

No. 16,738.

Patented June 15, 1886.

UNITED STATES PATENT OFFICE.

WALLACE KIRKPATRICK, OF ANNA, ILLINOIS.

DESIGN FOR A MODEL OF A PIONEER FARM.

SPECIFICATION forming part of Design No. 16,738, dated June 15, 1886.

Application filed April 7, 1886. Serial No. 198,163. Term of patent 3½ years.

To all whom it may concern:

Be it known that I, WALLACE KIRKPATRICK, of Anna, in the county of Union and State of Illinois, have invented and produced a new and original Design for a Model of a Pioneer Farm; and I do hereby declare the following to be a full, clear, and exact description of the invention, such as will enable others skilled in the art to which it pertains to make and use it, reference being had to the accompanying drawing, which forms part of this specification.

My invention consists of a design for a model of a pioneer farm, of which the accompanying photograph is a correct illustration.

The background A represents masses of rocks and trees. In the front of this background, at the center, is a field, B, which is inclosed by a worm fence, C, and in which persons are represented as both plowing and clearing away trees. At the right of this field is a water-fall, D, and from this water-fall runs

a stream or river, F, as shown. Near this water-fall is an emigrant camp, G, and close by is a bridge, H, which crosses the stream. 25 Near this bridge is also a party of men who are raising a log house, I. At the extreme left is a bridge, J, crossing the stream, and upon this bridge is an emigrant wagon. Near the bridge is a mill, O, and close by the mill is a 30 log cabin, P, which is inclosed by a worm fence.

Having thus described my invention, I claim—

The design for a model of a pioneer farm, 35 consisting of the parts A B C D F G H I J O P, as shown and described.

In testimony whereof I affix my signature in presence of two witnesses.

W. KIRKPATRICK.

Witnesses:

HUGH ANDREWS,
F. M. RENFRO.
